DOOR HOLDER

John Gulas, Sr., 4401 Wells St., Weirton, W. Va.
Filed Jan. 6, 1960, Ser. No. 753
5 Claims. (Cl. 292—275)

The present invention relates to devices for maintaining an edge mounted hinged closure member in fully or partially open position and, more specifically, to such a device which permits the position of the closure member to be readily changed.

Door constructions such as found in residences and commercial structures, comprise a door frame within which is mounted a door having one side edge pivotally connected to the frame for opening and closing movements. Such a door mounting is customarily provided with latch means to retain the door in fully closed position but, no means is provided for retaining the door in partially open position for ventilation or other purposes. Various other forms of hinged closure members for cupboards, lockers, windows and chests are frequently required to be held in partially open, fully opened or fully closed positions.

One object of the invention is to provide a holding device which automatically and frictionally retains the hinged closure member in any desired position between fully open and fully closed positions.

Another object of the invention is to provide a holding device of the character described with means for adjusting the frictional resistance of the device to change of position of the hinged closure member.

Another object of the invention is to provide a holding device of the character described which may be mounted within a hinged closure member where desired.

These and other objects will be made apparent from the following description of the invention and from the drawings forming a part thereof, wherein:

FIG. 1 is an isometric view of a portion of a door frame and door embodying the holding device;

FIG. 2 is a plan view of FIG. 1;

FIG. 3 shows a plan view of the holding device;

FIG. 4 shows a side elevation of the holding device;

FIG. 5 shows an end elevation of the holding device;

FIG. 6 shows an end elevation of the means for attachment of the device to a door frame;

FIG. 7 shows an end elevation of the means for attachment of the device to the door;

FIG. 8 shows a front elevation of the friction member; and

FIG. 9 shows a side elevation of the friction member.

Referring now to the drawings, a closure member such as door 1 is connected in the usual manner to a door frame 2 by hinge members 3 mounted flush with the adjacent faces of the door and frame and spaced along one vertical edge of the door. The holding device includes a body portion 4 for mounting within the door 1, a member 5 for attachment to the frame 2 and a flexible member 6 attached to member 5 and slidably movable within body portion 4 and door 1. As shown in FIG. 2 of the drawing the door 1 has an inwardly extending recess 7 of a depth to receive the inner end of flexible member 6 and of a vertical height to receive the said body portion 4.

The body portion 4 comprises an end plate 8 and spaced side walls 9 connected at one of their edges by an arcuate bottom wall 10. The opposite vertical edges of side walls 9 are connected by a rear wall 11 and to the adjacent face of end plate 8. The end plate 8 extends laterally of the side walls 9 for engagement with the hinged face of the door, as best shown in FIG. 3. Openings 12 in door plate 8 receive suitable fastening members securing the end plate to the door and retain said body portion 4 within the door recess 7. Opening 13 extending through plate 8

2

is of sufficient size to freely pass the flexible member 6 moving longitudinally within the arcuate body bottom wall 10. The member 5 has suitable apertures 14 therein for reception of fastening members securing the member 5 to door frame 1. One end of member 6 is secured to member 5 by any suitable means. As shown in FIGS. 4 and 6, member 5 has an aperture 15 therein through which one end of member 6 extends and is prevented from being withdrawn by a member 16 secured to member 6 and overlapping the adjacent face of member 5.

The adjustable means within body portion 4 frictionally engaging the member 6, comprises a pivotally mounted yoke member 17 having a friction member 18 mounted thereon and an adjusting screw assembly. The yoke 17 comprises a pair of spaced side walls 20 having the friction member 18 secured between them adjacent the lower ends thereof by screw fasteners 21, with the friction member depending below the side walls 20. As shown in FIGS. 8 and 9, the member 18 has a reduced portion 18a disposed between yoke walls 20 and a depending portion 18b extending below and substantially in the outer planes of said walls 20. Aligned apertures 22 in the side walls 9 of portion 4, the yoke 17 and friction member 18 receive a pivot pin 23 for pivotally mounting the yoke and friction member within portion 4. Depending friction member 18b has a downwardly inclined bottom face portion 18c which has a longitudinally extending concavity 18d therein for reception of the upper face of flexible member 6. Extending between the upper ends of the spaced yoke walls 20 is the shank 24 of the adjusting screw assembly. Shank 24 has mounted thereon, adjacent wall 8, a helical wound compression spring 25 with a bearing washer 26 at one end thereof abutting the spaced walls 20 of yoke member 17 between which the shank 24 extends to a journal support in end wall 11, the head 19 of shank 24 being mounted in wall 8. Between the yoke member 17 and wall 11, the shank 24 has mounted thereon a second washer 26a abutting the yoke, a second compression spring 25a and a nut 27 spaced from end wall 11 and compression spring 25a.

The holding device of the invention has been disclosed and described as mounted within a door hinged within a door frame. Obviously, the body portion 4 of the device may be mounted within or upon the door frame with the plate 5 secured to the door, if desired. This means of mounting the holding device is suitable where the door or other hinged closure member is relatively thin such as locker doors, lids on floor chests and windows mounted for hinging in a horizontal plane, for example.

The purpose of the device of the invention is to maintain a door or other hinged closure member in closed, open or any intermediate position by frictional resistance to sliding movement of flexible member 6 relative to body portion 4 thereof, while permitting manual movement of the door by a sufficient force to overcome said frictional resistance. The device when mounted, as shown in FIGS. 1 and 2, may have the frictional resistance to relative movement between flexible member 6 and friction member 18 varied at will by suitable rotation of adjusting screw 24.

Referring now to FIGS. 3, 4 and 8 of the drawing, the flexible member 6 may be of any suitable material, as shown it is a helical closely wound wire spring providing a substantially continuous outer surface. Member 6 has a close but free running fit within the arcuate bottom wall 10 of portion 4. The yoke 17 is pivotally mounted within portion 4 and is movable relative thereto upon suitable rotation of screw shank 24. The springs 25, 25a and washers 26, 26a are slidably mounted upon shaft 24 and the nut 27 is provided with internal threads engaging with the threads of screw shank 24. Since the head and end of the shank 24 are journaled in the opposite end walls of

portion 4 and spring 25a is initially compressed by nut 27, rotation of shank 24 in one direction causes nut 27 to move towards the yoke 17 further compressing spring 25a which in turn acts on adjacent washer 26a and the yoke 17 to rotate the yoke towards spring 25. Similarly rotation of shank 24 in the opposite direction causes nut 27 to move away from yoke 17 reducing the compression in spring 25a and spring 25 rotates yoke 17 towards end wall 11 of portion 4. This rotation of yoke 17 upon its pivot 22 is utilized to increase or decrease the bearing 10 pressure of member 18 upon member 6.

As shown in FIGS. 4, 8 and 9 pivot pin 22 of yoke 17 is to one side of the vertical center line thereof. The bottom face 18c of the friction member 18 slopes downwardly and has a concavity 18d parallel to face 18c and preferably shaped to conform to the arcuate top face of member 6. When yoke 17 is inclined to the left as in FIG. 4 to dispose the concavity 18d parallel to the top surface of member 6, the member 18 exerts minimum pressure upon member 6. Rotation of screw shank 24 to pivot yoke 17 to the right, increases the pressure of member 18 upon member 6 and increases the frictional resistance against relative movement between members 6 and 18. Such adjustment also provides compensation for wearing of friction member 18.

I claim:

1. A holding device providing adjustable resistance to a closure member hingedly mounted upon a supporting member for movement relative thereto, comprising a body portion recessed into an exposed face on one of said members adjacent said hinge mounting, a flexible member mounted on the other of said members and extending towards said body portion, aligned apertures in said body portion for passage of said flexible member through said body portion, a yoke pivotally mounted intermediate its ends within said body portion above said flexible member received therein, a friction member mounted on one end of said yoke in engagement with said flexible member moving within the body portion, and means rotatably mounted with said body portion engaging the opposite end of the yoke and accessible from an exposed face of said body portion for rotation of the yoke upon said pivot to regulate the resistance of the friction member to relative movement between the latter member and the flexible member.

2. A holding device providing adjustable resistance to movement of a door hinged at one vertical edge within a supporting frame, comprising a body portion recessed into said vertical door edge and secured thereto, a flexible

member secured to the adjacent portion of said frame and extending towards said body portion, aligned openings in said body portion receiving said flexible member for movement through the body portion, a friction member pivotally mounted within said body portion and continuously engaging said flexible member, and means on said body portion adjacent said door edge for imparting pivotal movement to the friction member for advancing the friction member into engagement with said flexible member.

3. The holding device as defined in claim 2, wherein said body portion has a surface below said friction member resisting deflection of the flexible member.

4. The holding device as defined in claim 3 wherein said friction member pivotal mounting is disposed to one side of the longitudinal center line of said member and the flexible member engaging face thereof slopes longitudinally of the plane of said face towards the opposite side of said longitudinal center line.

5. A holding device providing adjustable resistance to a hingedly mounted door member moving relative to a door frame member, comprising a body portion mounted with the one member, flexible means mounted on the other said member and extending therefrom towards said body

25 portion, said body portion having spaced side walls, connecting end walls and an arcuate bottom wall, aligned apertures in said end walls above said bottom wall receiving said flexible means moving through said body portion over said bottom wall, a yoke disposed between said housing side walls, a pivotal support for said yoke intermediate the ends thereof on said side walls, said pivotal support being disposed to one side of the longitudinal center line through said yoke, a friction member mounted on said yoke below said pivotal support and having a bottom face

30 thereon a portion of which continuously engages the adjacent face of said flexible means, said friction member bottom face sloping upwardly away from said flexible means, and means mounted in said body portion end walls in engagement with said yoke for adjusting the pressure of said friction member against said flexible means by moving said sloping frictional member face towards said flexible means.
